DOOR CHECK AND CLOSER.

No. 851,640.

Specification of Letters Patent.

Patented April 30, 1907.

Application filed February 16, 1906. Serial No. 301,357.

To all whom it may concern:

Be it known that we, JOSEPH BARDSLEY, a citizen of the United States, and a resident of Montclair, Essex county, New Jersey, and 5 ALBERT J. ROSENTRETER, a citizen of the United States, and a resident of Boonton, in the county of Morris and State of New Jersey, have invented certain new and useful Improvements in Door Checks and Closers, 10 of which the following is a specification.

The invention relates to improvements in door checks and closers, and consists in the novel features, arrangements and combinations of parts hereinafter described and particularly pointed out in the claims.

We present our invention herein as embodied in a check and closer adapted for screen and storm doors, and aside from the purpose of providing a highly efficient, durable, simple and inexpensive door check and closer, one object of the invention is to produce such device in a form adapted to lie within the narrow space found between the usual inside door and the outside screen or 25 storm door, the inner door ordinarily opening inwardly and the screen or storm door opening outwardly. The door check and closer may, however, be applied with equal convenience to a door opening inwardly. 30 The parts of our door check and closer are so disposed, in the preferred construction, that the door will stand in its wide open position when moved to that point.

One of the more essential objects of the invention is to provide a novel arrangement and disposition of the closing spring and its coacting parts, and another feature of the invention is the provision of a special construction and arrangement of lever and connecting rod for operating the piston, whereby the piston is given a rapid initial movement during the first part of the opening movement of the door, and the spring is enabled to exert its greatest power at the closing point of the movement of the door, at which point the greatest checking action is secured.

The invention also involves novel details of arrangement and construction adapting 50 the door check and closer to be adjusted to meet the various conditions which may be met in applying the same to practical use.

The invention will be fully understood

from the detailed description hereinafter presented, reference being had to the accompanying drawings, in which:

Figure 1 is a top view, partly broken away and partly in section, of a door check and closer embodying our invention, the same being illustrated as applied to the hinge-side 60 of a door, with the spring and cylinder secured to the lintel over the door and the connecting rod to the outer end of a bracket connected with the door; Fig. 2 is a front elevation, partly broken away, of same; Fig. 3 is 65 a front elevation of a portion of the lintel with the securing bracket and spring retaining and adjusting means applied thereto, Fig. 3 being partly in section on the dotted line 3—3 of Fig. 1, and the closing-spring being omitted therefrom; Fig. 4 is a detached view of the inner end of the checking cylinder; Fig. 5 is a section of same on the dotted line 5—5 of Fig. 4; Fig. 6 is a top view, partly broken away, of the door check and closer, 70 lintel and door, the latter being shown in its open position; Fig. 7 is a vertical section 75 through the securing bracket and spring adjusting means, on the dotted line 7—7 of Fig. 3; Fig. 8 is a longitudinal horizontal section 80 through a portion of the main securing bracket and lever arm pivoted thereto and is presented to illustrate more clearly the connection of the spring plunger-rod with said arm; Fig. 9 is a like section through the 85 outer end portion of the main securing bracket and is presented to more clearly illustrate the means for adjusting the tension 90 of the closing-spring. Fig. 10 is a top view of the bracket to which the connecting rod or link of the check and closer is pivotally secured, a portion of the said rod and a portion of the lintel being shown, and Fig. 11 is a vertical section of same on the dotted line 95 11—11 of Fig. 10.

In the drawings, 10 designates a door, 11 a door-jamb to which the door is hinged, as usual, and 12 the lintel over the door.

The door check and closer comprises a hinged checking cylinder 14, a pivoted operating yoke or two ended lever 15, a pivoted rod 16 connected with said yoke and a bracket 17, a piston rod 18 connected with said yoke, a cup-piston 19 carried by said rod 18 within said cylinder, a closing spring 20, and a co-acting spring plunger-rod 21 in pivotal en-

gagement with the inner end of said lever 15, which is at its middle portion pivotally secured to said piston rod and at its outer end pivotally connected with said rod 16, the inner end of said lever being pivotally connected with a bracket 22 which, in the present instance, is firmly applied to the lintel above the door. The cylinder 14 is at its outer end hinged to the outer end of said bracket 22, and the rod 16 is hinged to the bracket 17 which in the present instance is secured to the door 10. The cylinder 14 has upon its outer end a cap 23 and upon its inner end a cap 24, the latter being preferably pressed up from sheet steel and having a central opening surrounded by an integral flange 25 (Fig. 5) to afford a bearing for the piston rod 18. The cap 24 fits closely upon the cylinder 14 and is detachably held in place by the pins 26 passing through apertures in the sides of said cap and cylinder, as shown in Fig. 5, said pins being formed on the ends of a piece of spring wire 27, which is located against the outer face of the cap and extends around the piston rod, as shown in Fig. 4, the said wire being coiled and tempered to constitute a spring of contractile force adapted to bind the pins 26 within their receiving apertures and in the position shown in Fig. 5.

When it is desired to remove the cap 24 the pins 26 will by means of a screw-driver or other convenient implement, be forced outwardly from their receiving apertures. The pins 26 constitute spring-pins affording a very inexpensive and convenient means for detachably securing the cap 27 in place, and they dispense with screw threads and the like for such purpose. The cap 23 will also, preferably, be pressed up from sheet steel, and the said cap fits closely upon the outer end of the cylinder 14 and may be secured in place by solder or other convenient means. The cap 23 is formed integrally with an outwardly disposed perforated lug 28 to coöperate with the perforated lugs 29 on the bracket 22 pivotally connected thereto by the pin 30 by which the cylinder is hinged to said bracket. The cap 23 is also formed with an arm 31 which is bent into U-shape and apertured in line with a threaded aperture formed in the cap 23 and cylinder 14 (Fig. 6) to receive the point of a regulating screw 32, the said threaded aperture constituting an air vent and said screw affording means for more or less closing the same, so as to regulate the escape of air from the cylinder during the closing of the door. The aperture in the arm 31 is threaded to engage the thread on the screw 32, and the said arm has a limited outward spring tension so that when the entering end of the screw is in the vent aperture, the said arm 31 may, by its tension, place a binding force on said screw, thereby preventing the loosening or loss of the latter due to the jarring occasioned by the use of the door 10. The air

from the cylinder 14 escapes around the thread on the screw 32 and the passage of the air from the cylinder is resisted in proportion as the screw is worked inwardly into the vent aperture.

The cup-piston 19 carried by the piston rod is of ordinary form and construction requiring no special description.

The yoke or double-ended lever 15 is formed with apertured ears 34 which pass upon the eye at the exposed end of the piston rod 18 and through these ears and eye is passed a pin or rivet 35 by which said yoke or lever becomes pivotally secured to said rod. The yoke or lever 15 is of special outline having an angularly or diagonally disposed section 30 initially extending toward the inner end of the cylinder 14, where the ears 34 are formed, and a member or section 37 which initially extends rather closely along the cylinder 14 and substantially in parallelism therewith and with the lintel 12. The member or section 37 of the yoke or lever 15 is preferably bifurcated to receive between its upper and lower parts, when the door is closed, the outer portion of the rod 16, the outer end of the latter being pivotally secured to the outer end of said section 37 by means of a rivet or pin 38. The rod 16 initially lies substantially parallel with the lintel 12, as shown in Fig. 1, and its inner end is pivotally secured by a pin 39 to the bracket 17 fastened to the door.

The bracket 17 comprises an upper adjustable section 40 and a lower supporting section 41 adapted to be secured to the door by means of screws, as shown in Fig. 2, and which section curves outwardly from the door and then upwardly and is formed upon its upper end with an outwardly extending horizontal guide-way head 42, between the sides of which the adjustable section 40 is seated. The adjustable section 40 is formed with a recess 43 and slot 44, and at its outer end said section 40 is formed with a solid portion to receive the pin 39. The section 40 is fastened to the head 42 of the section 41 by means of a screw 45 and nut 46, said screw passing through an aperture in the head 42 and the slot 44 in the section 40 and into the nut 46 which rests within the recess 43 and spans the space between the side walls of the same. The head of the screw 45 presses against the lower surface of the head 42 and due to the engagement of the nut 46 with the upper surface of the section 40, binds said head and section together. The side edges of the nut 46 being in close relation to the walls of the recess 43, said nut is unable to turn or rotate within said recess during the tightening or loosening of the screw 45, and the relation of said nut to the walls of said recess also enables the section 40 to guide on said nut during the adjustment of said section 40 upon the head 42.

42 in a direction toward or from the door 10. When it is desired to adjust the section 40 it is simply necessary to slightly loosen the screw 45 and move the section 40 inwardly 5 or outwardly as may be desired, and then retighten said screw, the slot 44 permitting said section 40 to be moved upon the screw 45. The lower section 41 of the bracket 17 extends outwardly from the door and then 10 upwardly so that the upper portion of said section may extend upwardly and freely around any projecting molding or other portion of the lintel 12. In the construction shown in the drawings the face of the lintel 15 12 is parallel with the face of the door 10, but in many instances the lintel may be projected beyond the face of the door or possess a projecting molding around which the upper portion of the section 41 must extend, and in order to adapt the present device to the varying conditions to be met we 20 extend the upper portion of the section 41 first outwardly from the door and then upwardly and thence outwardly in the formation 25 of the head 42.

The bracket 22 is formed at its outer end with the aforesaid ears 29 to receive the pin 30 by which the outer end of the cylinder 41 is pivotally secured, and at its inner end the 30 said bracket is formed with substantially corresponding ears 47 between which the inner end of the yoke or lever 15 is secured upon the pin 48. A projection 49 (Fig. 8) of the lever 15 extends beyond the pivot pin 48 and 35 is at its outer end given the form of a vertical pin 50, the end of said lever about the pivot pin 48 being bifurcated and said pin 50 being integral with and connecting the upper and lower members of said bifurcated portion of 40 said lever 15.

The pin 50 affords a bearing for the inner end of the spring actuated plunger 21, said plunger having a head provided with a bearing recess 51 fitting upon said pin and maintained in such relation by the tension of the 45 spring 20 mounted thereon and which is confined between the shoulder 52 integral with said rod and a perforated plate 53 in which the outer end of said rod is movably mounted, 50 said plate being formed on a slide 54 mounted for this purpose in the bracket 22 and formed on its outer end with a plate 55 serving as a contact point for an adjusting screw 56 held within a threaded aperture in a rigid 55 portion 57 of said bracket and provided with an exposed head whereby it may be moved inwardly against the slide 54 or withdrawn outwardly therefrom.

The slide 54 is normally free to be moved 60 longitudinally on said bracket but is held against the screw 56 by the action of the spring 20, consequently will be substantially stationary during the opening and closing of the door and hence subserves the purpose of 65 an adjustable resistance against the pressure

of said spring and affords means whereby the initial tension of the spring may be regulated at will by means of the screw 56.

The slide 54 may be movably mounted in the bracket 22 in various ways, but a convenient method of mounting said slide consists in forming a longitudinal slot 60 in said bracket and in recessing the inner surfaces of said bracket adjacent to the walls of said slot, as shown in Fig. 7, to receive dove-tail 70 flanges 61 formed on said slide, said slide being thus permitted to move longitudinally of the bracket 22 and firmly held at its opposite edges thereby. The plates 53, 55 forming a part of the slide 54 are formed adjacent to 75 the edges of the bracket 22 with fingers 62 (Figs. 3 and 7) which ride on the bracket and aid in maintaining the due relation of the slide to said bracket; and between said plates 53, 55 the slide 54 is longitudinally recessed, 80 as at 63 (Fig. 7), to enable the rod 21 to have unobstructed movement. In the construction presented we provide for the application of the slide 54 to the bracket 22 after the latter has been secured upon the lintel 22, or 85 door as the case may be, and in respect of this part of our invention, we form notches 64 in the opposite edges of the runway for the slide, as shown in Fig. 3, of sufficient size to admit the flanges 61 formed on said slide, 90 and in introducing the slide to the bracket we simply place the slide in between the opposite edges of the bracket and move the flanges 61 through the notches 64 and then move the said slide 54 longitudinally of the 95 bracket so as to carry said flanges 61 from alinement with the notches 64 and into the inner recessed portion of said bracket, as indicated by the dotted lines in Fig. 3. The flanges 61 do not extend the entire length of 100 the slide 54, but are approximately of the size represented by the dotted lines in Fig. 3. The notches 64 are located at the outer end portion of the bracket 22 at a point at which no adjustment of the spring will require the 105 flanges 61 to become located during the use of the device. The slide 54 may also be withdrawn from the bracket 22 at any time desired without disturbing said bracket, to accomplish which it will simply be necessary to 110 withdraw the screw 56 to a sufficient extent for the spring 20 to push the slide outwardly until the flanges 61 thereof come opposite to the notches 64, at which time upon freeing the point of the screw from the slide the latter may be withdrawn free of said bracket. 115

The spring 20 is resisted by the plate 53 of the slide 54 and exerts its effective force against the projection 49 of the double ended lever 15. 120 The initial condition and relation of the parts of the apparatus, when the door is in closed position, is illustrated in Fig. 1, the lever 15 inclining outwardly and toward the cylinder 14 and thence extending along the 125 130

side of said cylinder and preferably on a line substantially parallel with the lintel 12 whereby the rod 16 may extend substantially parallel with said lintel and with the 5 section 37 of said lever 15.

The parts of the apparatus when constructed and arranged as shown in Fig. 1, occupy the minimum amount of space and may not only be used on the hinge-side of the 10 door, as shown, but also may be successfully employed on the other side thereof within the confined space usually allowed between the regular inner door and an outer screen or storm door, and while this is an important 15 consideration, the more essential advantage derived from the special construction and relation of the parts shown is that by reason thereof we are enabled to secure a very desirable action in the apparatus and in its effect 20 upon the door. During the opening of the door 10 the lever or yoke 15, during the first portion of such movement, rapidly assumes a position at right angles to the lintel and the projection 49 of said lever performs 25 its most rapid and effective movement against the plunger rod 21; said projection then being substantially in a right angular relation to the said rod and moving against it and then as the door continues on its opening 30 movement the lever 15 passing from its right angular relation gradually assumes a position more nearly parallel with the lintel 12 and the projection 49 of said lever gradually passes into line with the spring plunger rod 35 21, the spring exerting less and less effective force until finally when the door reaches its full open position, shown in Fig. 6, the said projection 49 will be substantially in line with the rod 21 and the spring although then 40 fully compressed will not act to close the door and the latter may stand open. During the closing of the door, the movement of the latter towards its closed position will first be gentle and thereafter as the projection 49 of the 45 lever 15 regains an angular relation to the spring plunger rod 21, the door will have an accelerated closing movement, with the result of creating the proper cushion in the outer end of the cylinder 12 and insuring the 50 firm closing of the door, the form and relation of the lever 15 with respect to the spring and other portions of the apparatus compelling, under the full force of the spring, the effectual closing of the door and the binding 55 of same in its closed position. The maximum force of the spring is utilized during the closing movement of the door and overcome during the initial opening of the door, the arrangement and the relation of the parts being 60 such that we attain the greatest spring power and the maximum check at the closing point of the door; and hence while the door is positively closed and held closed it is nevertheless prevented from banging.

65 A further advantage in the operation of

the closer and check arises from the fact that due to the bifurcation of the lever 15 to receive the outer end of the rod 16, the pull exerted by said rod during the opening of the door is always in direct central line with said lever and with the spring plunger rod 21. The rod 16 and piston rod 18 are on the same horizontal plane and on the plane of the horizontal central line of the lever 15 and spring plunger rod 21.

70

75

When it is desired to apply the door check and closer upon the side of a door opposite to the hinge-side thereof, the bracket 22 carrying the mechanism will be applied upon the door, and the outer end of the rod 16 will be 80 connected to a bracket (such as 70 in Fig. 1) secured to the door jamb.

What we claim as our invention and desire to secure by Letters Patent, is:—

1. The checking cylinder, the piston therein, the piston-rod connected therewith, the double ended lever pivoted at one end at a fixed point and at an intermediate point to said rod and having a projection (49) extending beyond said fixed point, the connecting 85 rod pivoted at one end to the outer end of said lever and at its other end to a fixed point, a closing spring exterior to said cylinder and confined at one end, and means operatively connecting the other end of said 90 spring to said projection of said lever, whereby said projection while said lever is turning on its pivot operates on and is operated by said spring; substantially as set forth.

2. The checking cylinder, the piston therein, the piston-rod connected therewith, the double ended lever pivoted at one end at a fixed point and at an intermediate point to said rod, the connecting rod pivoted at one end to the outer end of said lever and at its 100 other end to a fixed point, a closing spring exterior to said cylinder and confined at one end, and a rod in engagement with and acted on and acting against the other end of said spring, and provided with means to engage with the 105 inner end of said lever adjacent to its pivot point, whereby said end of said lever while turning on its pivot operates on and is operated by said rod and spring; substantially as set forth.

3. The checking cylinder, the piston therein, the piston-rod connected therewith, the double ended lever pivoted at one end at a fixed point and at an intermediate point to said rod and having a projection (49) extending 120 beyond said fixed point, the connecting rod pivoted at one end to the outer end of said lever and at its other end to a fixed point, a closing spring exterior to said cylinder and confined at one end, and a rod in engagement 125 with and acted on and acting against the other end of said spring and provided with means to engage with said projection of said lever inwardly beyond the pivot point thereof, whereby said projection while turning on 130

its pivot operates against said rod and spring; substantially as set forth.

4. The checking cylinder, the piston therein, the piston-rod connected therewith, the double-ended lever pivoted at one end at a fixed point and at an intermediate point to said rod, the securing bracket to which said cylinder and lever are connected, the connecting rod pivoted at one end to the outer end of said lever and at its other end to a fixed point, a rod slidably supported at one end from said bracket and at its other end being supported by its engagement with the inner end of said lever, a closing spring supported by said rod and at one end acting against the same, and means mounted in said bracket for the adjustment of said spring; substantially as set forth.

5. The checking cylinder, the piston therein, the piston-rod connected therewith, the double-ended lever pivoted at one end at a fixed point and at an intermediate point to said rod, the securing bracket to which said cylinder and lever are connected, the connecting rod pivoted at one end to the outer end of said lever and at its other end to a fixed point, a closing spring, a slide mounted in said bracket and having a plate 53 to act as a stop for one end of said spring, a screw 56 mounted in said bracket for adjusting said slide to regulate the tension of said spring, and a rod extending through said spring and guided in said plate and provided with means to engage the inner end of said lever adjacent to its pivot point, said rod being pressed against by said spring; substantially as set forth.

6. The checking cylinder, the piston therein, the piston-rod connected therewith, the double-ended lever pivoted at one end at a fixed point and at an intermediate point to said rod, the securing bracket to which said cylinder and lever are connected, the connecting rod pivoted at one end to the outer end of said lever and at its other end to a fixed point, a closing spring, a slide mounted in said bracket and having a plate 53 to act as a stop for one end of said spring, means for adjusting said slide along said bracket to regulate the tension of said spring, and a rod extending through said spring and guided in said plate and provided with means to engage the inner end of said lever adjacent to its pivot point, said bracket having the notches 64 and undercut recesses and said slide having the flanges 61 to pass through said notches and seat and move in said recesses, and said spring pressing at one end against said rod; substantially as set forth.

6. The checking cylinder, the piston therein, the piston-rod connected therewith, the double-ended lever pivoted at one end at a fixed point and at an intermediate point to said rod and provided adjacent to said fixed point with a projection 49 having a bearing

50, the securing bracket to which said cylinder and lever are connected, the connecting rod pivoted at one end to the outer end of said lever and at its other end to a fixed point, a closing spring, and a rod slidably supported from said bracket and extending through said spring and engaged by one end of the same and provided with bearing 51 to engage said bearing 50; substantially as set forth.

8. The checking cylinder, a piston therein, a piston-rod connected therewith, the double-ended lever pivoted at one end at a fixed point and at an intermediate point to said rod and thence extending along the front of said cylinder toward its outer end and about on a horizontal plane with the piston rod, a connecting rod pivoted to the outer end of said lever and thence returning along the same to a fixed point where it is pivoted, a securing bracket to which said cylinder and lever are secured, a closing spring confined at one end, and a plunger rod supported from said bracket and extending through said spring and provided with means to engage the end of said lever inwardly beyond the pivot point of same; substantially as set forth.

9. The hinged checking cylinder, the piston therein, the piston-rod connected therewith, the double-ended lever pivoted at one end at a fixed point and thence extending on a diagonal line to said rod to which it is pivoted and thence extending toward the outer end of said cylinder, and the connecting rod pivoted to the outer end of said lever and thence returning to a fixed point where it is pivoted, said connecting rod being at all times on the same horizontal plane with said piston-rod, and the outer portion of said lever being bifurcated to receive said connecting rod between its upper and lower members; substantially as set forth.

10. A door check comprising the cylinder, the piston therein, the piston rod connected therewith, the operating lever, and connecting rod, said lever being pivoted to said piston rod, and said cylinder having on its end a cap 24 and provided with a wire furnishing pins at its ends passing through apertures in the sides of the cap and cylinder, for detachably locking said cap in position; substantially as set forth.

11. A door check comprising the cylinder, operating lever, connecting rod, piston and piston-rod, said cylinder having a threaded escape aperture for air, a controlling screw therefor, and a spring arm containing a threaded aperture for said screw and adapted to exert a binding tension on said screw when the latter is engaged by the wall of said escape aperture; substantially as set forth.

12. In a door check, the checking cylinder, an operating lever therefor and a connecting rod at one end fastened to said lever, combined with the securing bracket to receive the other end of said rod, said bracket compris-

ing a supporting member 41, an adjustable member 40 seated thereon and means for binding said members together, one of said members having side flanges to preserve the alignment of the adjustable member with its support; substantially as set forth.

13. In a door-check, the checking cylinder, an operating lever therefor and a connecting rod at one end fastened to said lever, combined with the securing bracket to receive the other end of said rod, said bracket comprising a supporting member 41 having a head 42, an adjustable member 40 seated on said head and having a recess 43 and slot 44,

15 and a screw and nut for binding said members together, said nut being disposed in said recess, and said screw extending through said head and slot and engaging said nut; substantially as set forth.

Signed at New York, in the county and 20 State of New York, this 15th day of February, 1906.

JOSEPH BARDSLEY.
